UNITED STATES PATENT OFFICE.

ANTHONY COSTA, OF CLEVELAND, OHIO, ASSIGNOR TO THE GRAVITY CARBURETOR COMPANY, OF CLEVELAND, OHIO, A CORPORATION OF OHIO.

APPARATUS FOR ATOMIZING HYDROCARBON FUELS.

1,232,506.

Specification of Letters Patent. Patented July 10, 1917.

Application filed August 14, 1915. Serial No 45,584.

To all whom it may concern:

Be it known that I, ANTHONY COSTA, a citizen of the United States, and a resident of Cleveland, county of Cuyahoga, and State of Ohio, have invented a new and useful Improvement in Apparatus for Atomizing Hydrocarbon Fuels, of which the following is a specification, the principle of the invention being herein explained and the best mode in which I have contemplated applying that principle, so as to distinguish it from other inventions.

The subject of the present invention is a spray nozzle for use in atomizing various liquids and is particularly adapted for use in connection with a carburetor for securing an effective atomization of gasolene, kerosene and the like by means of a column of incoming air. In this type of devices it is highly desirable to break up the fuel so finely that no drops of liquid are drawn up by the incoming air as these drops do not actually atomize but are merely scooped up and thus do not give an intimate intermixing of air and fuel. It is the object of the present invention to entirely atomize all of the fuel supplied and to evenly and intimately intermix the same with air, which results in a much greater economy of fuel and in securing a greater amount of power from a given amount of fuel supplied. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Figure 1 is a transverse section through my improved spray nozzle taken on the line 1—1, Fig. 2; and Fig. 2 is a longitudinal section taken on the line 2—2, Fig. 1.

The general construction of this preferred form of my invention will be readily seen from these two figures. The device comprises a member preferably in the form of a circular disk 1 which is provided with an extension 2 upon one side which is attached to a fuel supply conduit 3. This disk 1 is provided with a central fuel supply pas-

sage 4 which opens into the passage formed in the fuel supply conduit 3 at one end and at the other end opens into a circular chamber 5. The disk 1 is provided with a plurality of longitudinally extending parallel openings or passages 6 which are disposed in a circle about the central chamber 5 as a center, these holes 6 being equidistant from the center of such circular chamber.

The disk is adapted to be placed in an upstanding flange 7 or chamber to be formed in a carburetor of any suitable type through which air will be drawn into the manifold leading to the engine on which the carburetor is used. Leading from the central chamber 5 to the air openings 6, are a plurality of radially disposed fuel supply passages 8 which preferably extend to the transverse and longitudinal center of the opening 6. That is, the conduits 9 extending from the ends of such passages, lead to the exact transverse center of such openings, and are so positioned that they are mid-way between the top and bottom of these passages 6. In this way a thin stream of fuel is supplied to the exact center of each of the air passages, and the result will obviously be the formation of a plurality of circular columns of air arising through these air openings. These series of columns of mixed air and fuel will pass up through the carburetor to the engine.

So small an amount of fuel is applied to each of the air openings that it will become intimately intermixed with the air passing therethrough and thus the entire rising column of mixed air and gas will be a perfect mixture in which there will be no unatomized fuel.

A plunger 10 is mounted in the top of the disk 1 and is provided at its lower end with a valve 11 adapted when desired to seat upon the upper edge of the conduit 4 thus closing the fuel supply passage. It will be understood that other means for throttling the supply of fuel may be used if desired. In actual operation the present invention has given very satisfactory results both as to economy and power secured from the engine on which it is used.

Other modes of applying the principle of my invention may be employed instead of the one explained, change being made as regards the mechanism herein disclosed, pro-

yided the means stated by any of the following claims or the equivalent of such stated means be employed.

I therefore particularly point out and distinctly claim as my invention:—

1. A liquid spray nozzle, comprising a member provided with a plurality of parallel air passages therethrough, and a central fuel supply passage, and a plurality of conduits extending laterally from such fuel passage to the central portion of such parallel passages, and said conduits lying at substantially right angles to the direction of movement of air through such passages.
2. A liquid spray nozzle, comprising a member provided with a plurality of parallel air passages therethrough, and a central fuel supply passage, and a plurality of conduits extending laterally from such fuel passage to the transverse centers of such parallel passages, and said conduits lying at substantially right angles to the direction of movement of air through such passages.
3. A liquid spray nozzle, comprising a member provided with a plurality of parallel

air passages therethrough, and a central fuel supply passage, and a plurality of conduits extending radially from such central fuel passage to the transverse and longitudinal centers of such parallel passages, and said conduits lying at substantially right angles to the direction of movement of air through such passages.

4. A liquid spray nozzle comprising a member provided with a central fuel supply nozzle and a plurality of equidistant surrounding, parallel air passages therethrough, and conduits extending radially from such fuel passage to the transverse and longitudinal centers of such parallel passages, and said conduits lying at substantially right angles to the direction of movement of air through such passages.

Signed by me, this 11th day of August 1915.

ANTHONY COSTA.
